UNITED STATES PATENT OFFICE.

JEAN BAPTISTE GUSTAVE ADOLPHE CANET, OF PARIS, FRANCE, ASSIGNOR
TO SIR JOSEPH WHITWORTH & COMPANY, (LIMITED,) OF OPENSHAW,
ENGLAND.

BREECH-LOADING CANNON.

SPECIFICATION forming part of Letters Patent No. 424,378, dated March 25, 1890.

Application filed February 7, 1889. Serial No. 299,006. (No model.) Patented in France June 20, 1887, No. 173,544.

To all whom it may concern:

Be it known that I, JEAN BAPTISTE GUSTAVE ADOLPHE CANET, engineer, a citizen of the Republic of France, and a resident of Paris, 5 France, have invented new and useful Improvements in Breech-Loading Cannon, (for which I have obtained a patent in France, Certificate of Addition No. 173,544, dated June 20, 1887,) of which the following is a specification, reference being had to the accompanying drawings.

My invention relates to breech-loading ordnance, and comprises the combination, with the breech-screw and a movable head and 15 stem fitted therein, of a bar of peculiar construction, which carries the firing-hammer and is arranged to slide transversely to the axis of the breech-screw, as hereinafter explained.

My said invention also comprises other improvements in the breech mechanism, as hereinafter set forth.

In the accompanying drawings I have shown how my said invention may be conveniently and advantageously carried into practice.

25 Figure 1 is a vertical longitudinal central section, and Fig. 2 a rear elevation, of the breech end of a gun having my present improvements applied thereto, the parts being shown in the positions which they occupy 30 when the breech-screw has been turned about its axis to disengage it from the screw-thread in the breech. Fig. 3 is a horizontal section on the line $x-x$, Fig. 2. Fig. 4 is a rear elevation partly in vertical section; Fig. 5 an under 35 side view; and Fig. 6, a horizontal central section, all drawn to an enlarged scale, showing details of construction.

A is the breech of the gun.

B is the breech-screw, which is provided 40 with an interrupted screw-thread.

C is a disk or head, which is provided with a rod or stem formed in two parts C' C², and fitted in a central recess or cavity provided for the purpose in the breech-screw B, so that 45 it is movable longitudinally therein, and the said head and stem can change their position according to the thickness and degree of compression of the obturator. The part C² of the stem has in its rear extremity a chamber a for the fuse or primer.

D D' indicate the sliding bar, which is formed in two parts. The part D thereof is fitted to slide in a radial groove b in the rear end of the breech-screw, and is provided with a stud or projection c, which works in a circular groove d in a piece d', firmly attached to the breech end of the gun. The part D is, moreover, provided with a projection or handle D², whereby it may be moved by hand. The other part D' of the said sliding bar is attached to 60 the part D thereof by means of a T-shaped piece e, formed on the part D', and fitted to slide in guides f formed on the part D, so that the part D', although movable with the head C and stem C' C², must participate in the 65 longitudinal movement of the part D. The part D' is secured to the stem C by a sleeve g fitted upon the said stem and secured thereon by means of a nut h countersunk in the said sleeve. The said part D' of the sliding bar is 70 fitted to slide transversely to the axis of the breech-screw between suitable guides formed on the said sleeve g.

The part D' of the sliding bar carries the firing-pin or striker j, and the part D thereof 75 carries the firing-hammer k, which is pivoted thereto at k', and is provided near its pivot with a roller l, against which bears a rod m, acted upon by a spring m', which is inclosed in a casing m², formed on the part D. This 80 arrangement is shown more clearly in Figs. 3, 4, 5, and 6. The hammer k is so formed that it can be readily cocked by hand.

n is a bent lever or sear, which is pivoted at n' to the part D of the sliding bar, and is 85 provided with an arm o. This arm serves as the trigger, and has a ring or eye for the attachment of the firing-cord. The arm n² of the sear n is adapted to enter a lateral recess or notch p in the boss of the hammer, as 90 shown in Fig. 4, when the said hammer is raised or cocked. The said arm n² is, moreover, acted upon by a spring n³, which retains it in the said recess or notch p, thus preventing the action of the hammer until the trigger is pulled to disengage the sear therefrom. The sear n is so arranged that should the hammer fall without the firing-cord being pulled, a projection k² on the said hammer 95 will come in contact with the said sear n, and 100

the hammer will thus have its movement arrested before it strikes the firing-pin *j*. Therefore the gun can only be discharged by pulling the firing-cord, and thus moving the 5 sear out of the path of the hammer and permitting the striking of the firing-pin thereby. A projection *q* on the sear prevents any movement of the trigger so long as the sliding bar is not in the proper position for the 10 discharge of the gun, in which position only the said projection *q* will be opposite a groove or notch provided for the purpose in the side of the groove *b* in the breech-screw, so that the trigger may act to release the hammer 15 and allow it to fall upon the firing-pin. The groove *d* is formed with an enlarged part *d*², so that when the breech is closed the sliding bar can be moved either upward to permit the extraction of an empty primer-case, or 20 downward to bring the firing-pin in line with the primer. The lower side of the said groove is made with an inclined or curved surface *d*³, which, when the breech-screw is turned to disengage it from the screw-thread in the 25 breech, moves the sliding bar upward, and thus brings the firing-pin out of line with the primer. Therefore the gun can only be discharged when the breech is completely closed and the sliding bar moved down.

30 I sometimes form the nut *g* in two parts, which are formed with grooves and which clamp the extremity of the movable stem *c'* *c*². In this case the said stem is introduced from the exterior and the disk screwed upon it. The result of this arrangement is that 35 the portion of the sliding bar mounted upon the said movable stem, while capable of participating in the movements of the said stem (the position of which varies, as above stated, 40 according to the thickness and degree of compression of the obturator) remains in engagement with the part of the said sliding bar carrying the firing and safety mechanism.

It is obvious that I can, if desired, somewhat further modify the construction of the mechanism without departing from the nature of my said invention.

What I claim is—

1. In a breech-loading gun, the combination, with the breech-screw, of a bar carried thereby and arranged to slide transversely to the axis thereof, a hammer and firing-pin carried by the said sliding bar, a projection on the said bar, a groove in the breech end of the 55 gun, (or in a piece attached thereto,) in which the said projection moves when the breech-screw is twined about its axis, and notches or recesses in the sides of the said groove, which, when the breech is closed, allow the 60 said bar to be moved in one direction to bring the firing-pin into line with the fuse or primer, or in the reverse direction to permit the extraction of the empty primer-case, for the purposes above specified.

2. In a breech-loading gun, the combination, with the breech-screw, the bar arranged to slide in a transverse groove therein, and

the hammer and firing-pin carried by the said bar, of a sear also carried by the said bar for retaining the said hammer in its cocked position, a trigger for disengaging the said sear from the hammer, and an arm which is attached to the said sear and bears against one side of the said groove, and which, when the sliding bar is moved into the firing position, arrives opposite a notch or recess in the side of the said groove, thus permitting the movement of the sear by the pulling of the trigger, for the purposes above specified.

3. In a breech-loading gun, the combination, with the breech-screw and the movable head and stem fitted therein, of a sliding bar carried by the said breech-screw and formed in two parts, one of which carries the firing-hammer and the other the firing-pin or striker, 85 and which are movable together transversely to the axis of the breech-screw, the part of the sliding bar which carries the firing-pin being movable with the said stem relatively to the other part of the said bar, for the purposes above specified.

4. In a breech-loading gun, the combination, with the breech-screw and the movable head and stem fitted therein, of a sliding bar formed in two parts connected together and 95 movable transversely to the axis of the breech-screw, substantially as described, a firing-hammer pivoted to one of the said parts, a firing-pin or striker carried by the other part, a sear for retaining the said hammer in its 100 cocked position, a trigger for disengaging the said sear from the hammer, an arm attached to the said sear and bearing against one side of the groove in which the said bar slides, and a notch or recess in the side of the groove, 105 which, when the said arm arrives opposite the same, permits the disengagement of the sear from the hammer, the sliding bar being provided with a projection working in a groove in the breech end of the gun and 110 adapted to enter one or the other of two notches or recesses in the sides of the said groove when the breech is closed to permit the movement of the sliding bar in one direction to bring the firing-pin into line with the primer 115 or in the reverse direction to permit the extraction of the empty primer-case, substantially as and for the purposes above specified.

5. In a breech-loading gun, the combination, with the breech-screw and the movable head and stem fitted therein, of a sliding bar formed in two parts D D', the part D of which 120 works in a transverse groove in the rear end of the breech-screw and the part D' of which is connected with the part D and with the 125 said movable stem and is free to move with either of them, a firing-hammer carried by the part D of the said bar, and a firing-pin or striker carried by the part D' thereof, substantially as and for the purposes above specified.

6. In a breech-loading gun, the combination, with the breech-screw and the movable head and stem fitted therein, of the sliding

- bar formed in two parts D D', connected together and movable transversely to the axis of the breech-screw, substantially as described, and carrying the hammer and firing-pin, the part D of the said bar being provided with a projection c and a groove d in the breech end of the gun (or in a piece attached thereto) in which the said projection moves when the breech-screw is turned about its axis, and notches or recesses in the sides of the said groove, which, when the breech is closed, permit the movement of the said sliding bar in one or the other direction, substantially as and for the purposes above specified.
7. In a breech-loading gun, the combination, with the breech-screw B, of the movable head C, provided with the stem formed in two parts C' C² and fitted to slide in the breech-screw, the sleeve g, fitted in the breech-screw and secured to the said stem, and the sliding bar formed in two parts D D', connected substantially as described, the part D of the said bar being fitted to slide in a transverse groove in the breech-screw and carrying the firing-hammer, and the part D' of the said bar being fitted to slide between guides on the said sleeve and carrying the firing-pin or striker, substantially as and for the purposes above specified.
8. In a breech-loading gun, the combination, with the breech-screw and the movable head and stem fitted therein, of the sliding bar, consisting of the parts D D', connected substantially as described, the hammer k, pivoted to the part D, the rod m, carried by the said part D and acted upon by a spring and bearing against the said hammer, the firing-pin or striker j, carried by the part D', and a sear n n² for retaining the said hammer in its cocked position until released by the pulling of the trigger, substantially as and for the purposes set forth.
9. In a breech-loading gun, the combination, with the breech-screw and the movable head and stem fitted therein, of the sliding bar, consisting of the parts D D', connected together and movable transversely to the axis of the breech-screw, substantially as described, the hammer k, pivoted to the part D and provided with the projection k² and notch p, the firing-pin or striker j, carried by the part D', and the sear n n², adapted to engage with the said notch in the hammer and extending into the path of the said projection k², except when the trigger is pulled, substantially as and for the purposes set forth.
10. In a breech-loading gun, the combination, with the breech-screw and the movable head and stem fitted therein, of the sliding bar, consisting of the parts D D', connected together and movable transversely to the axis of the breech-screw, substantially as described, the hammer k, pivoted to the part D, the sear n n², also pivoted thereto and provided with the arm q, the firing-pin j, carried by the part D', and a notch or recess in the breech-screw for permitting the disengagement of the said

sear when, but not until, the said sliding bar is moved into the firing position, substantially as and for the purposes set forth.

11. In a breech-loading gun, the combination, with the breech-screw and the movable head and stem fitted therein, of the sliding bar, consisting of the parts D D', connected together and movable transversely to the axis of the breech-screw, substantially as described, the hammer k, pivoted to the part D and provided with the projection k² and with the notch p, the sear n, also pivoted to the part D and provided with the arms n², o, and q, the firing-pin j, carried by the part D', and a notch or recess in the breech-screw, opposite which the arm q will arrive when the sliding bar is moved into the firing position, so that the movement of the sear by the pulling of the trigger can be effected when, but not until, the said firing-pin is in line with the fuse or primer in the gun, substantially as and for the purposes set forth.

12. In a breech-loading gun, the combination, with the breech-screw and the movable head and stem fitted therein, of the sliding bar, consisting of the parts D D', the former of which is provided with the projection c, the groove d in the breech-screw in which the said projection works, the firing-hammer k, pivoted to the part D and provided with the projection k² and notch p, the sear n, also pivoted to the said part D and provided with the arms n², o, and q, and a notch or recess in the breech-screw for permitting the movement of the sear by the pulling of the trigger when, but not until, the said sliding bar is moved into the firing position, substantially as and for the purposes set forth.

13. In a breech-loading gun, the combination, with the breech-screw, of the sliding bar D D', carried thereby and arranged to slide transversely to the axis thereof, and provided with the projection c, the hammer k, and firing-pin j, carried by the said sliding bar, a groove d at the breech end of the gun in which the said projection c moves when the breech-screw is turned about its axis, and which has an enlarged part d² for allowing the sliding bar to be moved when the breech is closed to bring the firing-pin into line with the primer or to permit the extraction of the empty primer-case, and an inclined or curved surface d³ on one side of the said groove, which, when the breech-screw is turned to disengage it from the screw-threads in the breech, automatically moves the sliding bar in such a manner as to bring the firing-pin out of line with the primer, substantially as and for the purposes set forth.

In testimony whereof I have hereunto signed my name in the presence of two subscribing witnesses.

JEAN BAPTISTE GUSTAVE ADOLPHE CANET.
